UNITED STATES PATENT OFFICE.

JOHN F. O'CONNOR, OF CHICAGO, ILLINOIS, ASSIGNOR TO WILLIAM H. MINER, OF CHAZY, NEW YORK.

SAFETY DOOR-OPERATING MECHANISM.

1,372,720.

Specification of Letters Patent. Patented Mar. 29, 1921.

Application filed October 30, 1919. Serial No. 334,571.

To all whom it may concern:

Be it known that I, JOHN F. O'CONNOR, a citizen of the United States, residing at Chicago, in the county of Cook and State of Illinois, have invented a certain new and useful Improvement in Safety Door-Operating Mechanisms, of which the following is a full, clear, concise, and exact description, reference being had to the accompanying 10 drawings, forming a part of this specification.

This invention relates to improvements in safety door operating mechanisms.

In the operation of railway dump cars of 15 various types, injury to operators has heretofore frequently occurred, during the unloading operation caused by the sudden loads imposed upon the operating shafts when the door operating mechanisms are released. Sudden loads on the shafts cause 20 the latter to rotate rapidly and this has frequently swung the claw bar or other operating tool in such a manner as to injure the operators.

25 The object of my invention is to provide a very simple and easily operable arrangement to be employed with the operating shafts of door operating mechanisms, the arrangement being such that lost motion of 30 any desired amount may be obtained between the part directly engaged by the operating tool and the main operating shaft of the door mechanism so that, when the doors are started in their opening movement with 35 the load thereon, the main operating shaft and the door mechanism will be free to rotate without causing rotation of that part directly engaged by the operating tool.

In the drawing forming a part of this 40 specification, Figure 1 is a side elevational view of a portion of a dump car showing my improvements in connection therewith. Fig. 2 is a vertical sectional view taken substantially on the line 2—2 of Fig. 1. Fig. 3 is a vertical sectional view taken substantially on the line 3—3 of Fig. 2. And Fig. 45 4 is a vertical sectional view corresponding substantially to the section line 4—4 of Fig. 2 but illustrating another embodiment of my 50 invention.

Referring first to the construction illustrated in Figs. 1, 2 and 3, 10 denotes a side sill of a car, and 110 a portion of the side wall or sheet. A portion of the main operating shaft of the door mechanism is indi-

cated at 11 and the same is suitably journaled at its outer end by means of a bushing 12 applied thereto, the bushing 12 being rotatably mounted in a bearing 13 provided by a depending bracket 14, which is riveted 60 or otherwise secured to the car structure. As will be understood by those skilled in the art, the links or other flexible connections between the shaft 11 and the doors may be of any suitable type and preferably will be of 65 that type wherein the parts are self-locked when the doors are in closed position. In other words, the door mechanism proper, when the doors are in closed position, will be such that the shaft 11 is free from torsional 70 strains and the shaft 11 will require a partial rotation in an unwinding direction in order to release the linkages and permit the doors to swing open. I do not consider it necessary to either illustrate or describe in detail 75 this part of the door mechanism since the general type is well known and illustrated in many prior patents and the specific form of connections between the shaft and the doors is immaterial in the use of my invention.

In carrying out my invention, I provide the shaft 11 with a sprocket wheel 15, the same being preferably riveted to the shaft 11 on the inner side of the bearing 13 so 85 that the sprocket wheel 15 and shouldered sleeve 12 will prevent endwise movement of the shaft 11. The bracket 14 is extended downwardly, as illustrated, and at its lower end is formed with another bearing 16 in 90 which is rotatably mounted a stud shaft 17. The latter, at its inner end, is provided with a sprocket gear 18 in the same plane as the sprocket gear 15 and a sprocket chain 19 cooperates with the two sprocket gears 15 and 95 18 in the well-known manner.

On the outer side of the bracket 14 the shaft 17 is provided with a disk-like flange 20 having near its periphery a radial lug 21. Coöperable with the lug 21 is another radial 100 lug 22 formed on the interior of a clutch member designated generally by the reference A. Said clutch member A is in the form of a casting and has an annular flange 23 which encircles the disk-like flange 20 of 105 the shaft or clutch member 17. The lugs 21 and 22 travel in the same vertical plane and it is evident that the lug 22 is adapted for independent rotative travel with respect to the lug 21 through an arc slightly less than 110

360°. In other words, the lug 22 may travel in a counterclockwise direction with respect to the lug 21, as viewed in Fig. 3, through an arc slightly less than a complete revolution.

- The clutch member A is provided with an outward extension 24 of square cross section adapted to receive the usual claw bar or other operating tool and by which it is directly actuated. The clutch member A is 10 further provided with a series of shoulders 25 around its periphery with which coöperates a pivoted locking dog 26 mounted on the bracket 14, said dog 26 being held by a cam plate 27 also pivoted to the bracket 15. To hold the elements of the clutch or 15 lost motion device properly assembled and also the sprocket wheel 18, a through-bolt 28 may be employed as clearly indicated in Fig. 2.
- 20 The operation is as follows: Assuming the doors in closed position and all of the parts as illustrated in Figs. 1, 2 and 3, the operator would first release the dog 26 to thereby permit rotation of the clutch member A. The operator would then apply the 25 claw bar to the clutch member A and rotate the latter in a counterclockwise direction which would cause the inner clutch member on said shaft 17 to rotate in a similar direction upon the engagement of the lugs 22 and 30 21. This in turn produces rotation of the sprocket wheel 18 which is communicated by the chain 19 to the sprocket wheel 15 and shaft 11. When the shaft 11 has been rotated 35 through a small arc sufficient to unlock the linkages, the shaft 11 will then be rotated under the weight of the load on the doors. Such rotation of the shaft 11 is permitted independently of the clutch member 40 A since the lug 21 will then be free to rotate in a counterclockwise direction as viewed in Fig. 3, relative to the lug 22 through an arc of slightly less than 360°. This prevents any sudden movement of the clutch member A and hence eliminates the danger 45 to the operator. In this connection it may be stated that in some door operating mechanisms, a lost motion of less than 360° is sufficient whereas in others a lost motion

greater than 360° is desirable. With my 50 construction, it is evident that either of these conditions can be simply met by using sprocket wheels 15 and 18 of proper diameters. In the construction shown, the sprocket wheel 15 is of lesser diameter than 55 the sprocket wheel 18 and consequently more than a complete revolution of lost motion is obtained between the clutch member A and the shaft 11, as will be understood.

In the form illustrated in Fig. 4, the arrangement of parts is identical with that illustrated in Figs. 1, 2 and 3 except that instead of using sprocket wheels and a sprocket chain, I employ two meshing gear wheels 115 and 118. The diameters of the 60 gear wheels 115 and 118 may be varied as in the case of the sprocket wheels and explained in the preceding description. The only difference in the result between the construction shown in Fig. 4 and that illustrated 65 in the other figures is that the direction of rotation of the main operating shaft relative to the direction of rotation of the clutch member A will be reversed, that is, in the construction illustrated in Figs. 1, 2 and 3, 70 the shaft 11 will rotate in the same direction as the clutch member A whereas in Fig. 4, the shaft 111 will rotate in the opposite direction to the rotation of the stud shaft or clutch member 117. 75

I claim:

In a door operating mechanism, the combination with a bracket adapted to be secured to a car and having a pair of parallelly arranged adjacent bearings, of a door 80 operating shaft journaled in one of said bearings, an auxiliary shaft journaled in the other of said bearings, power-transmitting means between said shafts; a clutch element rotatable in unison with the auxiliary shaft, 85 and a tool-operated clutch element coöperable with the first-named clutch element and rotatable a predetermined distance relatively thereto.

In witness that I claim the foregoing I 90 have hereunto subscribed my name this 10th day of Oct. 1919.

JOHN F. O'CONNOR.
